Fig. 5

FIG. 1 is a left side elevational view of my design for a collapsible automobile camper, with the camper being in its collapsed position.

FIG. 2 is a left side elevational view of the camper, similar to FIG. 1, but in the extended position.

FIG. 3 is a front elevational view of the camper in a collapsed position.

FIG. 4 is a front elevational view of the camper, similar to FIG. 2, but in its extended position.

FIG. 5 is a rear elevational view of the camper in its extended position.

The right side view of the camper in the collapsed position and, the right side view of the camper in the extended position appears the same as the left side views, that is, FIGS. 1 and 2. The rear view of the camper in the collapsed position appears the same as the front view of the camper in its collapsed position, that is FIG. 3.

The automobile shown in broken lines is included for illustrative purposes only.

I claim:

The ornamental design for a collapsible automobile camper, as shown and described.
